NECKTIE

Thomas L. Lang, Baltimore, Md.

Application October 6, 1932. Serial No. 636,596

3 Claims. (Cl. 2—150)

This invention relates to neckties and more particularly to a necktie of the four-in-hand type.

An object of this invention is to provide a necktie of this character with a preformed knot which is so constructed that it will not readily wrinkle.

Another object of this invention is to provide a necktie having a preformed knot to adjustably receive the slidable or narrow end of the tie.

10 A further object of this invention is to provide in a tie of this character, a resilient plate formed to hold the parts of the tie in desired shape, the plate being suitably covered with the material of which the tie is formed.

15 The above and various other objects and advantages of this invention will in part be described and in part be understood from the following detailed description of the present preferred embodiment, the same being illustrated in 20 the accompanying drawing, wherein:—

Figure 1 is a fragmentary front elevation of a tie constructed according to the preferred embodiment of this invention.

25 Figure 2 is a fragmentary rear elevation of the tie showing the manner of slidably mounting the loose end or rear portion of the tie in the knot.

Figure 3 is a rear elevation of the knot forming member showing the manner of constructing 30 the knot part.

Figure 4 is a view with the covering portion of the knot shown in partly raised position.

Figure 5 is a plan view of the reinforcing plate.

35 Figure 6 is a plan view of the inner padding member which engages the plate shown in Figure 5.

Figure 7 is a detail plan view of the plate having the padding member shown in Figure 6 40 mounted thereon.

Figure 8 is a detail side elevation of the securing pin for holding the loose end of the tie in adjusted position within the knot.

45 Figure 9 is a plan view of the cushioning member disposed beneath the outer covering of the tie.

Referring to the drawing wherein like numerals of reference designate corresponding parts throughout the several views, the numeral 8 designates generally the front portion of a tie constructed of desired material, and the numeral 1 designates the rear end portion or the slidable member which is adapted to slide through the knot of a four-in-hand tie when disposed about 55 the neck of the wearer.

In order to provide suitable means to prevent wrinkling of the tie at the knot, I have provided a metallic plate 4 which is provided with a straight lower end portion 4a, upwardly divergent side edges 4b, and a curved upper edge portion 4c. 60 This plate is provided with an upper elongated slot or opening 9 and a lower elongated opening 10, the purpose for which will be hereinafter described.

A padding member 3 of relatively heavy texture constructed of a configuration similar to the plate 4 but having a length slightly in excess of this plate, is adapted to engage the outer face of the plate 4, and the opposite ends of the padding 3 are bent inwardly, as shown in Figure 70 7, and secured by stitching 6 or the like, which stitching passes through holes 6a provided in the plate 4 adjacent each side edge thereof.

An elongated pin 2 is secured as by a clip 2a to the rear face of the plate 4, and this pin 2 75 is provided with an angularly disposed upper end portion 2c to prevent turning of the pin. The lower end of this pin 2 is bent angularly, as at 2b, the purpose for which will be hereinafter described.

80 A second padding member 7 is adapted to be mounted on the outer surface of the inner padding 3, and an outer covering 5 engages about the padding 7, and is suitably secured thereabout. This covering 5 is of a similar texture to the texture of the tie portion 8. The tie portion 8 is stitched, as at 8a, to the paddings 3 and 7, and the length of this slot 10 is substantially equal

85 to the width of the upper end of the tie portion 8 so that the upper end of the tie portion 8 90 can be secured to the paddings 3 and 7 through the plate 4. The sliding portion 1 has one end thereof free and the opposite end is secured as by stitching 1a to the padding 3 through the slot 9. This slot 9 is disposed on one side of the 95 center of the plate 4 so that when this plate is bent in the formation of a knot, as shown in Figures 1 and 2, the attached end of the tie member 1 will be disposed on an angle to the tie portion 8.

100 When the paddings 3 and 7 are secured to the plate, the tie members 1 and 8 are stitched to the inner padding 3 through the slots 9 and 10 respectively. The knot covering 5 may be reversed and the lower end disposed uppermost 105 and sewed with the member 8. This member 5 may then be brought upwardly over the outer face of the outer lining or padding 3 and then brought over the top of the plate 4 and sewed on the inside of the knot as shown by stitching 12 110

in Figure 2. The plate 4 is then bent as shown in Figure 2 with the opposite ends 4b spaced apart.

The slideable tie portion 1 can then be pulled downwardly through the knot member, and when this tie portion 1 is tightened to the desired degree, the free end portion 1 can then be moved inwardly a slight degree so that it will contact with the bent portion 2b of the securing member 2, which will pierce the free end 1 and prevent further upward movement thereof, and thereby prevent loosening of the loop about the neck of the wearer. By providing a securing member, as shown in Figure 2, wherein the bent portion 2b projects outwardly and projects below the bottom of the plate 4, when it is desired to remove the tie from the neck of the wearer, the free end portion 1 is first pulled downwardly so as to free this member from the securing member 2, whereupon the point of the pin 2 may be protected by a finger or the like, and the free end 1 then slid out of the knot either through the opening 11 or pulled longitudinally through the knot.

It will be noted, from the foregoing, that a tie construction has been disclosed wherein the knot will not wrinkle during the use of the tie, and wherein the free or looped portion of the tie can be tightened to the desired degree without injury to the free end portion. The material from which the tie proper is constructed may be of any desired character.

It is, of course, understood that various changes and modifications may be made in the details of construction and design of the above specifically described embodiment of this invention without departing from the spirit thereof, such changes and modifications being restricted only by the scope of the following claims.

40

What is claimed is:—

1. In a necktie construction, a knot forming means comprising a relatively rigid plate having a pair of elongated substantially horizontal slots therein, a fixed tie member, means for securing the member to the plate through one of the slots, a slideable tie member, and means for securing an end of the slideable tie member to the plate through the other of the slots.

2. A necktie construction comprising a fixed tie portion, a slideable tie portion, a knot forming plate bent in the form of a loop with free rear end portions spaced apart, said plate having a pair of elongated horizontally disposed slots therein, a padding secured to one face of the plate, means for securing one end of the fixed tie portion to the padding on the opposite side of the plate through one of the slots, means for securing one end of the slideable tie portion to the padding on said opposite side of the plate through the other of the slots, a covering about the padding, and means carried by the plate and extending therebelow and engaging the slideable tie portion to hold said latter portion in adjusted position relative to the plate.

3. In a necktie construction, a knot forming means comprising a metallic plate having a pair of elongated horizontally disposed slots therein, a padding about the plate, means for securing a fixed tie member to the padding through one of the slots, means for securing one end of a slideable tie member to the padding through the other of the slots, an elongated pin, means for securing the pin to the plate whereby one end of the pin will project below the plate, said pin having a forwardly projecting lower end portion, and means for preventing turning of the pin relative to the plate.
